VACUUM CLEANER

Jack L. Burgoon, Toledo, Ohio, assignor to American-Lincoln Corporation, Toledo, Ohio, a corporation of Ohio

Filed Aug. 29, 1966, Ser. No. 3,622

Term of patent 14 years

(Cl. D49—11)

Fig. 1

Fig. 2

FIG. 1 is a view in perspective of a vacuum cleaner embodying my new design;

FIG. 2 is a top plan view thereof;

FIG. 3 is a right side elevational view thereof;

FIG. 4 is a bottom view thereof;

FIG. 5 is a front end elevational view thereof; and FIG. 6 is a rear end elevational view thereof.

The side not shown has substantially the same appearance as the side shown.

The handle portions are omitted in FIGS. 4, 5, and 6 and shown broken away in FIG. 3 for convenience of illustration.

The dominant features of my design reside in the portions shown in full lines.

The broken line showings of the motor and bag have been omitted in FIGS. 2-6 for convenience of illustration.

I claim:

The ornamental design for a vacuum cleaner, substantially as shown and described.
